(57) **CLAIM**

We claim the ornamental design for a handheld barcode scanner, as shown and described.

DESCRIPTION

FIG. 1 is a perspective view of a handheld barcode scanner showing our new design from the front, top, and right side; FIG. 2 is another perspective view thereof shown from the front, bottom, and right side;

FIG. 3 is another perspective view thereof shown from the rear, top, and left side;

FIG. 4 is a right side elevation view thereof, the left side elevation view being a mirror image thereof;

FIG. 5 is a front elevation view thereof;

FIG. 6 is a rear elevation view thereof;

FIG. 7 is a top plan view thereof; and,

FIG. 8 is another perspective view thereof shown from the rear, bottom, and left side.

The broken lines are directed to unclaimed features and form no part of the claimed design.
